UNITED STATES PATENT OFFICE.

FRANZ KRATZ AND GOTTLÖB HONOLD, OF STUTTGART, GERMANY, ASSIGNEES TO THE
FIRM OF ROBERT BOSCH, OF STUTTGART, GERMANY.

ELECTRIC SWITCH.

1,183,079.

Specification of Letters Patent.

Patented May 16, 1916.

Application filed March 9, 1915. Serial No. 13,200.

To all whom it may concern:

Be it known that we, FRANZ KRATZ, a subject of the Emperor of Germany, residing at and whose post-office address is Schlossstrasse 59^a Stuttgart, Germany, and GOTTLÖB HONOLD, a subject of the Emperor of Germany, residing at and whose post-office address is Militärstrasse 4, Stuttgart, Germany, have invented certain new and useful Improvements in Electric Switches; and we do hereby declare the following to be a full, clear, and exact description of the invention, such as will enable others skilled in the art to which it appertains to make and use the same.

The electric switch of the present invention embodies improvements especially applicable in electric starting systems for internal combustion engines on automobiles, motor boats, and other moving vehicles.

The features of novelty will be particularly pointed out in the following description, and the appended claims, taken in connection with the accompanying drawings in which—

Figure 1 is a sectional elevation through the switch in the depressed position; Fig. 2 is a section on line 2—2 of Fig. 1; Figs. 3 and 4 are sections corresponding to Figs. 1 and 2, with the switch locked in its inoperative position; Fig. 5 is a view of the removable key; Fig. 6 is a section on line 6—6 of Fig. 1, drawn on an enlarged scale; Fig. 7 is an enlarged horizontal section through a switch bridge; Fig. 8 is a section on line 8—8 of Fig. 7; and Fig. 9 is a section on line 9—9 of Fig. 7. Fig. 10 is a side elevation of the switch partly in section. Fig. 11 is a front view showing an inserted resistance. Fig. 12 is a rear view. Fig. 13 is a horizontal section in the line 13—13 of Fig. 12.

The hollow switch shaft *b* is longitudinally movable in the bearing *a'* of the switch housing *a*, and it carries a head member *c* having a hinged cap *d*. The lock bar *e* is fitted in the interior of the switch shaft and is provided at the upper end with the key hole *f* and at the other end with the projecting tongues *g* adapted to slide in the slots *h* of the upstanding stationary guide post *i*. These slots terminate in horizontal locking slots *h'* into which the tongues *g* may be turned to lock the switch shaft against depression from its raised position,

the lock bar *e* being longitudinally movable with the switch shaft and rotatable therein. A removable key *g* fits in the key hole *f* and is adapted to turn the lock bar *e* when tongues *g* are in registry with the locking slots *h'* to thereby lock the switch in inoperative position against unauthorized use, and to unlock the switch shaft for movement to its operative position, the cap *d* being provided for the purpose of preventing the entrance of foreign matter into the switch housing at other times. The coil compression spring *k* presses against the head of the post *i*, and the under side of the head member *c*, thus tending to hold the switch shaft *b* in its raised position, shown in Figs. 70

The switch shaft *b* carries the conducting switch bridge *l* and also an arm *l'*, which cooperates with the conducting switch bridge *l* slidably mounted on the upstanding guide post *i'*. The metal contact studs *m* are mounted on the insulating material *w* and are electrically connected to the binding posts *m'*. The studs may be segmental and also variously arranged to produce the desired sequence of circuit connections upon depression of the switch shaft. The switch bridge *l* is adapted to maintain a set position, the arm *l'* moving it from the position shown in Fig. 3 to that shown in Fig. 1, or 80 in the opposite direction, upon engaging the lower or upper rims of the sleeve *l* which is fast with the switch bridge *l* and slidable on the post *i'*. The switch bridges *l* and *l* are alike, and each is composed of bent laminations of thin metal riveted together at *l* and held between two clamping plates *n* with flanges *p* which extend around substantially half of the outer circumference of that part of the switch bridge that encircles 90 the switch shaft *b*. The insulation *l* insulates the switch shaft *b* and the posts *i*, *i'*, from the switch bridges *l* and *l*. The nut *o*, screwed on the end of the switch shaft forces the switch bridge against the member *o'*, 100 and thereby holds the plates *n* clamped against the edges of the laminations *l* or *l*.

It will be observed that the contact surfaces of the studs *m* lie in parallel planes, which, together with the arrangement of the laminations *l*, *l*, and the fastening means therefor, brings about an equalization of the pressure on the studs such that neither the

switch shaft *b* nor the sleeve *b* is forced to a vertically inclined position. In this way binding action is prevented.

A resistance made up of one or more strips *r* of nickelin, or other suitable metal, is laid around the sides and bottom of the switch housing *a*. The resistance metal is insulated on both surfaces by strip mica *s*, and the outside is covered by a metal sheet *u* fastened to the switch housing *a* by rivets extending between the strips. The two ends of strip *r* are electrically connected to binding posts *v* which may be connected to the binding posts *m'* or to the circuit, according to any desired arrangements.

Having thus described our invention, what we claim is:

1. In an electric switch, the combination with contact studs, a conducting switch bridge 20 slideable along said contact studs, and a longitudinally movable switch shaft fastened to the switch bridge and constructed and arranged to move the switch bridge from an inoperative to an operative position 25 in engagement with the contact studs, of locking mechanism preventing the movement of the switch bridge to its operative position and comprising a locking bar carried by the switch shaft so as to turn relatively thereto, and a catch coöperative with 30 the locking bar when the locking bar is turned relatively to the switch shaft.
2. In an electric switch, the combination with switch studs, a conducting switch bridge 35 slideable along said contact studs, an upstanding post having a longitudinal guiding slot terminating in a horizontal locking slot, and a longitudinally movable switch shaft constructed and arranged to move the 40 switch bridge longitudinally, of a locking bar carried by the switch shaft and having a tongue slideable in the guiding slot and rotatable in the locking slot, and a removable key for turning the tongue into the locking 45 slot to thereby lock the switch shaft against

longitudinal movement when the switch bridge is disengaged from contact studs.

3. In an electric switch, the combination with contact studs, a conducting switch bridge slideable along said contact studs, and a longitudinally movable switch shaft having a hinged cover on which the operating pressure is applied and being constructed and arranged to move the switch bridge from an operative position in engagement with the contact studs, of key locking mechanism embodying a removable key insertible in operative position when its cover is raised to lock the switch bridge against movement to its operative position.

4. In an electric switch, contact studs having contact surfaces lying in parallel planes, a conducting switch bridge of resilient material engaging the studs, a switch shaft fastened to the switch bridge and having a smooth interior and a post on which the switch shaft is freely slideable and also freely rotatable to permit turning movement thereof for equalizing unbalanced pressure between the switch bridge and the studs.

5. In an electric switch, contact studs having contact surfaces lying in parallel planes, a conducting switch bridge of bent laminations having edge on contact with the studs, apertured clamping plates having flanges 75 embracing the laminations at the bent portion to prevent spreading thereof, a switch shaft passing through the clamping plates and fastened thereto, and a bearing rotatably mounting the switch shaft to permit turning movement thereof for equalizing unbalanced pressure between the switch bridge and the studs.

In testimony whereof we affix our signatures, in presence of two witnesses.

FRANZ KRATZ.
GOTTLÖB HONOLD.
